CLAIM

The ornamental design for a motorcycle, as shown and described.

DESCRIPTION

1.1 is a right-side elevation view of a motorcycle embodying our new design;

1.2 is a left-side elevation view thereof;

1.3 is a front elevation view thereof;

1.4 is a rear elevation view thereof;

1.5 is a top plan view thereof;

1.6 is a bottom plan view thereof; and

1.7 is a top, front and right-side perspective view thereof. The broken lines in the drawing depict portions of the motorcycle that form no part of the claimed design.

1 Claim, 7 Drawing Sheets
